UNITED STATES PATENT OFFICE.

EDWARD W. GOODWIN, OF DETROIT, MICHIGAN.

DESIGN FOR A COMBINATION AUTOMOBILE BODY, HOOD, AND FENDERS.

Application filed October 29, 1927. Serial No. 23,922. Term of patent 7 years.

To all whom it may concern:

Be it known that I, EDWARD W. GOODWIN, a citizen of the United States, residing at Detroit, in the county of Wayne and State of Michigan, have invented a new, original, and ornamental Design for Combination Automobile Body, Hood, and Fenders, of which the following is a specification, reference being made to the drawings, forming a part thereof.

In the annexed drawings Fig. 1 is an elevation; Fig. 2 is a plan view; Fig. 3 is a front elevation; Fig. 4 is a rear elevation of an automobile in accordance with my invention.

I claim:

The ornamental design for a combination automobile body, hood, and fenders, as shown.

E. W. GOODWIN.
